WILLIAM H. HOOPER, OF LYNN, MASSACHUSETTS, ASSIGNOR, BY MESNE ASSIGNMENTS, TO THOMAS G. PLANT, OF BOSTON, MASSACHUSETTS.

CHANNEL-MOISTENING DEVICE FOR SEWING-MACHINES.

940,691.

Specification of Letters Patent. Patented Nov. 23, 1909.

Application filed December 23, 1907, Serial No. 407,682. Renewed April 14, 1909. Serial No. 489,849.

To all whom it may concern:

Be it known that I, WILLIAM H. HOOPER, of Lynn, in the county of Essex and State of Massachusetts, and a citizen of the United States, have invented an Improvement in Channel-Moistening Devices for Sewing-Machines, of which the following description, in connection with the accompanying drawings, is a specification, like numerals 10 on the drawings representing like parts.

The invention to be hereinafter described relates to channel moistening devices employed in connection with sole sewing or fastening machines in the manufacture of boots and shoes.

It has heretofore been proposed to provide some machines of this general character with devices for moistening the channel of boots and shoes to facilitate the insertion of the 20 fastening means, but such devices have either acted periodically or were started and stopped by the machine stopping and starting means. As well known by those skilled in the art, each of these devices, as thus proposed, is open to objection; the former on account of wear and tear incident to its rapid movements and the power necessary for its operation, and the latter owing to the fact that the action of the moistening device 25 was restricted solely to the periods of machine operation.

The present invention aims to overcome these and other objections incident to such prior devices, and provide a moistening device which may be thrown into action either with or without starting the sewing or other fastener inserting machine, which may remain continuously in operation until after the machine has stopped, and be thrown out 40 of action by a reverse movement of such machine.

In some types of sewing or other fastener inserting machines it is desirable that the operating parts be brought to rest in predetermined position, as, for instance, with the needle raised, and that such action be secured without shock. In such machines, after the driving power has been disconnected, the momentum of the moving parts 50 is utilized to wind up a spring, which thereafter acts to reverse the machine and bring it to rest in the desired predetermined position, all as pointed out in application Ser. No. 404,795, filed Dec. 2, 1907, to which 55 reference may be had. The present me-

chanical embodiment of my invention is shown and described herein as applied to such general type of sewing machine but is obviously not circumscribed or restricted in this respect beyond the limitations pointed out in the claims.

In the drawings:—Figure 1 is an elevation of the present embodiment of the invention, as applied to a sewing machine of the general character referred to, only so much of such machine being illustrated as desirable to show the relation of the invention thereto, and some parts being shown in section. Fig. 2 is a detached detail of the channel guide and liquid supplying nozzle.

The driving shaft 1 is suitably supported upon a frame 2, and has loosely mounted thereon a belt pulley 3, constituting the loose member of a clutch. Also appropriately secured to the driving shaft to rotate therewith is the fast clutch member 4, the two members constituting the friction clutch of usual form, being relatively movable upon the driving shaft 1 by a treadle controlled rod 5 to place them in driving or 75 non-driving relation, as will be readily understood by those skilled in the art, and as pointed out in my application hereinbefore mentioned.

A spring 6 has one end secured at 7 to the 85 clutch member 4 which is secured to rotate with the driving shaft, and its other end secured at 8 to the initial stopping arm 9 loosely mounted upon the hub of the clutch member 4, said stopping arm 9 having a 90 projecting portion 10, adapted to contact with the stop-finger 11 when the latter is moved into the path of said stopping arm 9.

The stop-finger 11 is mounted to slide longitudinally of the stud 12 and is caused to 95 move by means of a spring 13 acting upon an arm 14 secured to a rocking sleeve 15, which in turn is connected to the sleeve 16 of the stop-finger 11, by means of arm 17; a treadle rod 18 serving to move the stop-finger 11 in the opposite direction as pointed out in the application hereinbefore mentioned.

The face of the fast clutch member 4 is provided with a stop 18, which, upon reverse 105 movement of the clutch member 4 under the recoil of spring 6, is adapted to engage the stop-finger 11 and bring the parts to rest in the desired predetermined position. A 110 brake 19 carried by the stop-finger sleeve 16

is caused to act upon the clutch member 4 when the latter is engaged by the projecting portion 10 of the stopping arm 9.

The parts so far described are and may be all as pointed out in the application hereinbefore mentioned and need no further description.

In the operation of the machine, the treadle rod 18* will be depressed and the 10 stop-finger 11 moved from engagement with the parts 10 and 18, and the clutch members 3 and 4 will be placed in driving relation by means of the treadle rod 5. When the machine is to be stopped, treadle rods 5 and 18* 15 will be released, thus disengaging the clutch members 3 and 4, and the stop-finger 11 will be moved by its spring 13 into the path of the projection 10 of the stopping arm 9, which will consequently be brought to rest. 20 Under the momentum of the machine the fast clutch member 4 will continue to move in the direction of the arrow, Fig. 1, until the increasing tension of spring 6 brings it to rest, whereupon the spring 6 will reverse 25 the clutch member 4 and the machine parts connected to shaft 1, until the stop 18 on said clutch member engages the stop-finger on the side thereof opposite the projection 10, whereupon the clutch member 4 and 30 shaft 1 will be brought to rest with the machine parts in the desired predetermined position.

The parts and the operation thus far described are or may be the same as in the application before mentioned.

Mounted upon a suitable bracket 20 secured to the machine frame is a tank 21 in which water or other desirable moistening liquid may be placed. Connected to said 40 tank is an outlet 22, having a tubular screw stem 23 engaged by a screw nut 24, and containing an ordinary valve and its operating crank arm. To the lower portion of the outlet 22 is connected a conduit 26 leading to a 45 nozzle 27 preferably communicating with a passage way or opening 29 in the channel guide 28. The outlet end of this passage-way or opening is adjacent the lower end of the channel guide 28 so that water or other 50 liquid flowing thereinto from the conduit 26 will be directed into the channel of the shoe sole in advance of the awl and needle.

Pivotedly connected to the bracket 20 or other suitable part at 30 is a bell crank or 55 other lever, one arm 31 of which is connected to a treadle rod 32, the other arm 33 of which is connected to a valve crank 25 by means of a link 34. The connection of link 34 with the arm 33 is preferably made by a 60 slot 35 in the arm 33 and a set-screw or pin 36, whereby the amount of valve movement and consequent flow of liquid may be adjusted and regulated to the needs of the particular work. From this construction it will 65 be obvious that by means of the treadle rod

32 the valve may be opened and closed independently of the machine operation.

Secured to the arm 33 of the bell crank lever is a valve closer 37 having at its end a toe 38 which, in the normal operation of 70 the machine in the direction of the arrow, Fig. 1, rides over the cam 39 secured to the driving shaft 1, said cam having an abrupt end 40. A spring 41 connected to the valve closer 37 and bracket 20 normally acts to 75 depress the free end of the valve closer 37, so that after the machine has been stopped and upon its reverse movement, the end 40 of the cam 39 engages the toe 38 and moves the valve closer to the left, Fig. 1, thereby 80 closing the valve. The reverse movement of the shaft 1 is sufficiently quick in action to throw the end of the valve closer some distance beyond the position of final rest of the cam end 40, so that space is afforded be- 85 tween the toe 38 and end of the cam 39 to permit movement of the valve closer 37 to the right, Fig. 1, by means of the rod 32 to open the valve. Such opening of the valve may be made at the same time as the 90 machine is started, if desired, or may be opened later, because the treadle rod 32 is not connected to the starting and stopping mechanism; and when once opened it may remain continuously open until after the 95 stopping mechanism acts and until the machine is reversed, or it may be closed at any time by hand.

Owing to the independent treadle control of the valve opening movement, it is obvious 100 that such valve may be turned more or less to allow an amount of liquid to pass through the conduit suitable to the work being done, and such regulation of liquid supply is directly under control of the operative.

While the particulars described are well suited as one mechanical form of the invention, it is not to be understood that these particulars are essential since they may be variously modified within the skill of the artisan without departing from the true 110 scope of the actual invention as defined by the claims.

What I claim is:—

1. A work moistening device, comprising, 115 in combination, a source of liquid supply, a conduit leading therefrom to the work, means moved by the operator for rendering said device effective for the delivery of liquid to the work, and power means, including a shaft, operative when the shaft is given reverse movement for closing said conduit.

2. In a machine for treating leather, a 120 shaft, and a work moistening device, comprising, in combination, a source of liquid supply, a conduit leading therefrom to direct liquid to the work, a valve in said conduit, means controlled by the operator for opening said valve, and means operative 125

130

upon reverse movement of said shaft for closing said valve.

3. In a machine of the type described, an operating shaft, a moistening device having 5 a valve means connected therewith adapted by its movement to open and close said valve, and a cam operative on reverse movement of said shaft to actuate said means to close the valve.

10 4. In a machine of the type described, the combination of a shaft and operating means therefor, a channel guide provided with a passage, a moistening device having a supply conduit communicating with said passage, a valve controlling said conduit, means for moving the valve to open the conduit and means operative on reverse movement of the shaft for closing said valve.

5. In a machine for treating leather, a 20 shaft, and operating means therefor, a tool driven from said shaft, a moistening device having a valve to control the supply of liquid, and a supply conduit leading to the work being treated, means arranged to open 25 said valve independent of the machine starting devices, and means operative after the machine has been stopped and upon reverse movement of said shaft to close said valve.

6. In a machine of the character described,

the combination of a shaft, fast and loose 30 clutch members associated therewith, means for disengaging said clutch members and bringing said shaft to rest in a predetermined position, a moistening device, a valve connected therewith and permitting it to 35 remain continuously open during the machine operation, and means operative subsequent to the disengagement of the clutch members and by the approach of the shaft to its predetermined position of rest to close 40 said valve.

7. In a machine of the character described, the combination of a shaft, driving means associated therewith, means for disengaging the driving means therefrom, devices for reversing the movement of said shaft after the disengagement of the driving means, a moistening device, and means operative with reverse movement of the shaft for rendering 45 said moistening device ineffective.

In testimony whereof, I have signed my name to this specification, in the presence of two subscribing witnesses.

WILLIAM H. HOOPER.
